UNITED STATES PATENT OFFICE.

FRANK P. D'ARCY, OF KALAMAZOO, MICHIGAN.

UPHOLSTERING DEVICE.

1,283,098.

Specification of Letters Patent. Patented Oct. 29, 1918.

Application filed July 13, 1918. Serial No. 244,787.

To all whom it may concern:

Be it known that I, FRANK P. D'ARCY, a citizen of the United States, residing at the city and county of Kalamazoo, State of Michigan, have invented certain new and useful Improvements in Upholstering Devices, of which the following is a specification.

This invention relates to improvements in upholstering devices.

The main objects of this invention are:

First, to provide an improved upholstering device which facilitates the manufacture of cushions having flute-like tufts or a fluted surface.

Second, to provide an improved upholstering device which greatly increases the output of upholsterers in the manufacture of cushions such as automobile seat cushions.

20 Third, to provide an improved upholstering device which may be successfully operated by others than skilled upholsterers.

Further objects, and objects relating to structural details, will definitely appear from 25 the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Figure I is a perspective view of my improved upholstering device with the parts adjusted in one position, press bars being indicated by dotted lines.

Fig. II is an end elevation with the parts in the position shown in Fig. I.

40 Fig. III is a vertical longitudinal section on a line corresponding to line 3—3 of Fig. I, parts of a cushion in process of manufacture being shown in order to better illustrate the method of use.

45 Fig. IV is a vertical longitudinal section corresponding to that of Fig. III with the parts adjusted to another position.

Fig. V is a perspective view of the removable side of the filler box having follower bars attached thereto.

Fig. VI is a perspective view of one of the partition plates.

50 Fig. VII is a detail view showing details of one of the guide and ratchet members.

55 Fig. VIII is a detail vertical section through one of the guide and ratchet mem-

bers on a line corresponding to line 8—8 of Figs. II and VII.

Fig. IX is an enlarged detail section on a line corresponding to line 9—9 of Fig. II, 60 showing details of the retaining means for the removable side of the filler box.

Fig. X is a detail vertical section on a line corresponding to line 10—10 of Figs. II and XI, showing details of the operating connections for the ratchet mechanism.

Fig. XI is a detail section on a line corresponding to line 11—11 of Figs. II and X.

Fig. XII is a detail longitudinal section illustrating the manner of engaging the 70 backing securing clips.

Fig. XIII is a detail plan view further illustrating the manner of engaging the backing securing clips.

Fig. XIV is a detail section through one 75 of the tufting bars.

In the drawing, similar reference characters refer to similar parts throughout the several views, and the sectional views are taken looking in the direction of the little 80 arrows at the ends of the section lines.

Referring to the drawing, I provide a form 1 having a fluted bottom 2 with tufting bars 3 disposed between the flutes so that the upper edges of these bars project above 85 the bottom so as to support the cushion at spaced intervals to facilitate manufacture. These bars have spaced notches 4 on their upper edges, the advantage of which will appear as the description proceeds.

I provide removable partition plates 5 having slots 6 in their lower edges adapted to engage the projecting tufting bars. These partition plates are preferably formed of a piece of sheet metal folded upon itself with 90 their edges spaced to form the slot 6, the rivets 7 retaining the parts in position.

The filler box 8 is provided with a removable side 9, the side being retained by the spring clips 10 pivoted at 11 on the ends of 100 the filler box to swing over the keepers 12,—see Fig. IX.

This removable side carries a series of follower bars 13 spaced so as to pass between the partition plates and the tufting 105 bars,—see Figs. I, III, IV and XII.

The form is provided with guide posts 14 having ratchet teeth 15 thereon while the filler box 8 is provided with coacting guides 16 provided with ratchet members or pawls 110 17. To simultaneously actuate these pawls to release them and also as a means of ap-

plying spring pressure thereto I provide levers 18 pivoted at 19 on the guide members and connected by the links 20 and 21 and the levers 22 disposed at the corners of the 5 filler box.

A spring 23 connected to the filler box and to one of the levers 22 urges all of the ratchet pawls to their engaging position. A disengaging lever 24 is pivoted at 25 10 and connected to one of the links 20 so that they may be simultaneously disengaged.

I have illustrated my invention as I have adapted it in practice in the manufacture of cushions shown in my application for 15 Letters Patent filed concurrently herewith.

In the manufacture of cushions I first arrange the cushion cover 26 in the form so that it sags into the flutings of the bottom, being supported at intervals by the tufting 20 bars. The cushion skirt 27 is turned back over the form as indicated and the backing 28 is turned over the fixed side and end walls of the filler box. The partition plates 5 being in position the filling material is 25 arranged between these plates as indicated in Fig. III and the side 9 adjusted to position and the press actuated to press the material as indicated in Fig. IV. The partition plates 5 are then removed and the 30 backing folded down or arranged over the follower bars and secured as indicated in Fig. XII.

I preferably secure the backing by means of the clips 3, the bars being notched to 35 permit the ready engagement of the clips or where stitched to permit the convenient stitching as is shown in my companion application.

After the backing is secured the removable side is disengaged, the follower bars being withdrawn longitudinally and the cover secured at the remaining edge which completes the upholstering portion of the cushion.

45 By the use of my improved form I am able to manufacture cushions very rapidly, and this may be done in a practical manner by others than skilled upholsterers.

I have illustrated and described my improved upholstering device in the form in which I have embodied the same for the manufacture of cushions having fluted surfaces or flute-like tufts. I have not attempted to illustrate or describe certain 50 modifications which I contemplate as I believe the disclosure made will enable those skilled in the art to which my invention relates to embody or adapt the same as may be desired.

60 Having thus described my invention, what I claim as new and desire to secure by Letters Patent, is:

1. In an upholstering machine, the combination of a form having a fluted bottom, 65 tufting bars disposed between the flutes, re-

movable partitions having slots in their lower edges engageable with said tufting bars, a filler box provided with a removable side having follower bars thereon adapted to pass between said removable partition plates and said tufting bars permitting the removal of the partition plates and the arranging of a backing over said follower bars and the securing thereof at said tufting bars, means for securing said detachable 70 filler box side permitting the longitudinal withdrawal of said follower bars, guide posts on said form provided with ratchet teeth, guide members on said filler box co-acting with said guide posts and provided with retaining ratchets, and operating connections whereby said ratchets may be simultaneously released.

2. In an upholstering machine, the combination of a form having a fluted bottom, 85 tufting bars disposed between the flutes, removable partitions having slots in their lower edges engageable with said tufting bars, a filler box provided with a removable side having follower bars thereon adapted 90 to pass between said removable partition plates and said tufting bars permitting the removal of the partition plates and the arranging of a backing over said follower bars and the securing thereof at said tufting bars, and means for securing said detachable 95 filler box side permitting the longitudinal withdrawal of said follower bars.

3. In an upholstering machine, the combination of a form, spaced tufting bars, removable partitions having slots in their lower edges engageable with said tufting bars, a filler box provided with a removable side having follower bars thereon adapted to pass between said removable partition plates and said tufting bars permitting the removal of the partition plates and the arranging of a backing over said follower bars and the securing thereof at said tufting bars, means for securing said detachable 100 filler box side permitting the longitudinal withdrawal of said follower bars, guide posts on said form provided with ratchet teeth, guide members on said filler box co-acting with said guide posts and provided with retaining ratchets, and operating connections whereby said ratchets may be simultaneously released.

4. In an upholstering machine, the combination of a form, spaced tufting bars, removable partitions having slots in their lower edges engageable with said tufting bars, a filler box provided with a removable side having follower bars thereon adapted to pass between said removable partition plates and said tufting bars permitting the removal of the partition plates and the arranging of a backing over said follower bars and the securing thereof at said tufting bars, and means for securing said detachable 110 115 120 125 130

able filler box side permitting the longitudinal withdrawal of said follower bars.

5. In an upholstering machine, the combination of a form having a fluted bottom, 5 tufting bars disposed between the flutes, removable partitions engageable with said tufting bars, and follower bars adapted to pass between said removable partition plates and said tufting bars permitting the removal of the partition plates and the arranging of a backing over said follower bars and the securing thereof at said tufting bars, said follower bars being longitudinally removable.

10 6. In an upholstering machine, the combination of a form having spaced tufting bars, removable partitions engageable with said tufting bars, and follower bars adapted to pass between said removable partition 20 plates and said tufting bars permitting the removal of the partition plates and the arranging of a backing over said follower bars and the securing thereof at said tufting bars, said follower bars being longitudinally removable.

25 7. In an upholstering machine, the combination of a form having a fluted bottom, tufting bars disposed between the flutes, a filler box provided with a removable side 30 having follower bars thereon adapted to pass between said tufting bars permitting the arranging of a backing over said follower bars and the securing thereof at said tufting bars, means for securing said detachable filler box side permitting the longitudinal withdrawal of said follower bars, 35 guide posts on said form provided with ratchet teeth, and guide members on said filler box coacting with said guide posts and 40 provided with retaining ratchets.

45 8. In an upholstering machine, the combination of a form, spaced tufting bars, a filler box provided with a removable side having follower bars thereon adapted to pass between said tufting bars permitting the arranging of a backing over said follower bars and the securing thereof at said tufting bars, means for securing said detachable filler box side permitting the longitudinal withdrawal of said follower bars, 50 guide posts on said form provided with ratchet teeth, and guide members on said filler box coacting with said guide posts and provided with retaining ratchets.

55 9. In an upholstering machine, the com-

bination of a form having a fluted bottom, tufting bars disposed between the flutes, a filler box provided with a removable side having follower bars thereon adapted to pass between said tufting bars permitting the arranging of a backing over said follower bars and the securing thereof at said tufting bars, and means for securing said detachable filler box side permitting the longitudinal withdrawal of said follower bars.

10. In an upholstering machine, the combination of a form, spaced tufting bars, a filler box provided with a removable side having follower bars thereon adapted to 70 pass between said tufting bars permitting the arranging of a backing over said follower bars and the securing thereof at said tufting bars, and means for securing said detachable filler box side permitting the 75 longitudinal withdrawal of said follower bars.

11. In an upholstering machine, the combination of a form having a fluted bottom, tufting bars disposed between the flutes, 80 and removable partitions having slots in their lower edges engageable with said tufting bars.

12. In an upholstering machine, the combination of a form, spaced tufting bars, and 85 removable partitions engageable with said tufting bars.

13. In an upholstering machine, the combination of a form having a fluted bottom, tufting bars disposed between the flutes, and 90 follower bars adapted to pass between said tufting bars permitting the arranging of a backing over the follower bars and securing thereof at said tufting bars, said follower bars being longitudinally removable. 95

14. In an upholstering machine, the combination of a form, spaced tufting bars having spaced notches in their edges, and follower bars adapted to pass between said tufting bars permitting the arranging of a 100 backing over the follower bars and securing thereof at said tufting bars, said follower bars being longitudinally removable.

In witness I have hereunto set my hand and seal in the presence of two witnesses. 105
